BAG

Ossip Joseph Wallinsky, New York, N. Y.

Application April 14, 1933, Serial No. 666,137

3 Claims. (Cl. 150—35)

This invention relates to bags and is applicable to hand-bags both of the frame type adapted to be pendants carried by a handle, or of the envelop type usually carried under the arm of the user.

The objects of the invention are to provide a bag particularly adapted for carrying an auxiliary container; to provide an auxiliary container which is readily accessible at all times; to avoid the necessity of opening the bag for removing the auxiliary container; to render the auxiliary container completely removable; to secure simplicity of construction and operation; and to obtain other advantages and results as may be brought out in the following description:—

Referring to the accompanying drawing in which like numerals of reference indicate similar parts throughout the several views;

Figure 1 is an elevation of a bag embodying my invention;

Figure 2 is a longitudinal sectional view on line 2—2 of Figure 1; and

Figure 3 is an end view looking at the right hand end of Figure 1; and

Figure 4 is a vertical sectional view on line 4—4 of Figure 1.

In the specific embodiment of the invention illustrated in said drawing, the reference numeral 1 indicates the pouch portion of a bag which in this instance has been shown as of the envelop type. The bag, may, however be constructed in any suitable manner, and the particular showing herein of the chosen bag is merely because of necessity to show some bag regardless of its detailed construction.

According to one feature of the present invention, an auxiliary container 2 is to be carried in the pouch and is to be inserted therewith or withdrawn therefrom through an opening 3 in the end drawn therefrom of the pouch as distinguished from the usual top opening 4 of the pouch. In this connection it may be stated that the bag preferably includes a flap 5 by which the usual top opening 4 of the pouch may be normally closed. In order to insert or withdraw the auxiliary container 2, it is unnecessary, in accordance with the present invention to uncover said usual opening 4 of the pouch or to raise or otherwise disturb the normal closed position of flap 5.

In the preferred adaptation of the invention as illustrated, the bag includes end members or gussets 6, constituting opposite ends for the pouch. These gussets enable the pouch to expand when contents are inserted in the pouch. According to my invention, an intermediate gus-

set 7 is provided constituting a dividing wall so that the pouch provides a pair of pockets 8—8 one of which is adjacent one end gusset and the other which is adjacent the other end gusset. This feature of having an intermediate gusset 7 similar to and disposed between end gussets is perhaps an important feature of the present invention and an advance in hand-bag construction, affording individual compartments the filling of any one of which does not tend to crush contents of another. It is furthermore of especial advantage in connection with the above described construction in which an auxiliary container 2 is inserted through an opening 3 in one end gusset 6. When such arrangement is provided, as shown, the container will then be positioned within the pocket 8 next to that end gusset having opening 3. The other pocket is undisturbed by introduction or withdrawal of the auxiliary container in the first mentioned pocket, and its contents are not subject to loss or likely to be spilled from the gusset opening 3 during the time said auxiliary container is removed.

Means are preferably provided for retaining the auxiliary container assembled within the pouch except when it is desired to remove the container for use. As one means for accomplishing this purpose, I have shown a strap or tab 9 secured to or forming an integral part of the auxiliary container, said tab having an outer end which may be swung around to one face of the bag and temporarily secured thereon by means of a snap fastener 10. As here shown, the end margin of the flap 5 is cut away at 11 so that said tab 9 may be brought into direct engagement with the pouch surface a major part of which is beneath flap 5. For convenience this side of the bag will be considered its front and it will thus be noted that both the flap and the tab are at the front of the bag and that each may be manipulated without disturbing the other. Tab 9 constitutes means by which the container may be withdrawn as well as means for securing the container within the bag. It will be understood that the container is especially adapted for such uses as a cigarette case, powder case, change container, and the like and has the very desirable advantage of being adapted to complete detachment and removal from the bag so that the owner of the bag does not have to hold same open or expose the contents of the bag when either extracting the auxiliary container or while using the same.

Obviously detail changes and modifications may be made in the construction and use of my

improved bag without departing from the spirit or scope of the invention, and I do not wish to be understood as limiting myself to the exact construction shown and described except as set forth 5 in the following claims when construed in the light of the prior art.

Having thus described my invention, I claim:—

1. A bag as characterized comprising a pouch having end gussets, an intermediate gusset similar to said end gussets for dividing the interior from end to end of the bag into successive pockets, means for closing all of said pockets at one edge of the pouch for gaining access to all of said pockets thereat as desired and one of said 15 gussets having a lateral opening therethrough for providing a secondary means of access to one of said pockets.

2. A bag as characterized comprising a pouch having a normal opening and means for closing 20 the same, an auxiliary container for insertion in said pouch, the interior of the portion of the pouch receiving said container being accessible through said normal opening, said pouch having

25 another opening for inserting and withdrawing said auxiliary container without disturbing the normal closure for the pouch, access to the container-receiving portion of said pouch thereby being had at will through either the normal opening or the second mentioned opening, said auxiliary container substantially fitting the second mentioned opening and comprising a closure therefor.

3. A bag as characterized comprising a pouch having a normal pouch opening and means for closing the same, an auxiliary container for insertion in a portion of said pouch accessible through said normal top opening and entirely removable at will from the pouch, said pouch having an end opening for inserting and withdrawing said auxiliary container without disturbing the normal closure for the pouch, said auxiliary container substantially fitting the second mentioned opening and comprising a closure therefor.

OSSIP JOSEPH WALINSKY.
